W. C. MOORS.
SHADE ROLLER STOP.
APPLICATION FILED DEC. 4, 1920.

1,403,340.

Patented Jan. 10, 1922.

UNITED STATES PATENT OFFICE.

WALTER C. MOORS, OF OWENSBORO, KENTUCKY.

SHADE-ROLLER STOP.

1,403,340.

Specification of Letters Patent. Patented Jan. 10, 1922.

Application filed December 4, 1920. Serial No. 428,345.

To all whom it may concern:

Be it known that I, WALTER C. MOORS, a citizen of the United States, residing at Owensboro, in the county of Daviess and 5 State of Kentucky, have invented certain new and useful Improvements in Shade-Roller Stops, of which the following is a specification, reference being had therein to the accompanying drawing.

10 The present invention relates to a shade roller stop or lock, and is particularly an improvement over the devices shown in my Patents Nos. 1,242,362 and 1,329,092, granted Oct. 9, 1917, and Jan. 27, 1920, respectively.

15 It is the object of the present invention to improve the construction and assemblage of the component elements, whereby the device can be more cheaply constructed and the parts readily assembled and applied to a 20 shade roller, so that the device will operate to stop or lock the roller should it rotate at an excessive speed, and thereby avoid the "flying up" and injury to the shade.

25 A further object is the provision of such a device comprising cap or ferrule to fit over the end of a shade roller, and a disk fitted within said cap or ferrule and carrying the dog and its spring, and means for attaching said disk and cap together, whereby to provide 30 a compact and efficient construction, said cap and disk being readily stamped from sheet metal.

35 With the foregoing and other objects in view, which will be apparent as the description proceeds, the invention resides in the construction and arrangement of parts hereinafter described and claimed, it being understood that changes can be made within the scope of what is claimed without departing 40 from the spirit of the invention.

The invention is illustrated in the accompanying drawing, wherein:—

Figure 1 is a front view of the improved shade roller stop or lock, portions being 45 broken away and shown in section.

Fig. 2 is a cross section on the line 2—2 of Fig. 3.

Fig. 3 is a longitudinal horizontal section on the line 3—3 of Fig. 1.

50 Fig. 4 is a perspective view of the cap or ferrule.

Fig. 5 is a perspective view of a modified form of bracket having a stop for the roller.

In the drawing, there is illustrated a portion 55 of a shade roller 1 on which the shade 2 is wound, said roller being provided at one

end (not shown) which the usual pawl and ratchet device which releases by centrifugal action to permit the shade to be wound up as usual. The end of the roller shown has a 60 pivot pin or spindle 3 mounted for rotation in the bracket 4 as usual, and this end of the roller is provided with the improved device.

The bracket 4 is provided with a lug or stop finger 5 extending at right angles therefrom parallel with and at one side of the axis of the roller 1, for the engagement of the dog 6 which is pivotally connected to or mounted at the end of the roller 1. This dog 6, as shown, is disposed loosely between a 70 disk 7 and the disk or head 8 of a cap or ferrule, and said dog is pivotally mounted on a pin or rivet 9 secured to and carried by the disk 7. The rim 10 of the cap or ferrule is adapted to slip and fit over the end of the 75 roller, in applying the device to the roller, and the disks 7 and 8 have apertures 11 through which the pin or spindle 3 extends. The device is readily applied by slipping it on the end of the roller over the spindle 3, 80 and by substituting the ordinary bracket by the bracket 4 having the lug 5.

The outer edge of the dog 6 is curved, as at 12, and a doubled wire spring 13 is disposed between the disks 7 and 8, and its 85 bend embraces a headed lug or rivet 14 secured to and carried by the disk 7 diametrically opposite to the pin or rivet 9. The spring 13 extends partially around the spindle 3, with one terminal bearing against the 90 outer curved edge 12 of the dog 6, and the other terminal of the spring bearing outwardly against the marginal flange 20 of the disk 7. The dog is provided at its free end with an abutment 16, and with an inwardly extending portion 17 to contact with the spindle 3, for limiting the inward movement of the dog. The spring 13 extends in the same general direction as the dog, and has its free terminal overlapping the dog, so 100 that the free end of the dog is unobstructed and capable of moving outwardly from between the disks.

The device is secured to the end of the shade by means of a screw 19 or other securing element extending through apertures in the disks 8 and 7 and taking into the roller, whereby to hold the device in place.

The marginal flange 20 of the disk 7 extends away from the roller toward the disk 110 8, and fits snugly within the rim 10 of the cap and abuts the disk 8. This flange 20 has

ears or lugs 21 extending therefrom at several points and passing through slots or apertures 22 in the disk 8, and said ears are bent to overlap the disk 8, and thereby securely hold the disk 7 within the cap. Thus, in manufacture, the disk 7 and cap can be readily stamped from sheet metal, and the dog 6 and spring 13 readily secured to the disk 7 by means of the pins or rivets 9 and 14. In assembling the device, the disk is inserted into the cap and the ears 21 inserted through the apertures 22 and then bent. The rim 10 of the cap and flange 20 have a slot or opening 23 for the outward movement of the dog 6 to engage the lug 5.

During the normal speed of rotation, the roller 1 in winding up the shade 2, the spring 3 will resist the tendency of the dog 6 to swing outwardly by centrifugal force, so that the roller will not be locked or stopped accidentally during the winding up of the shade. However, should the shade slip out of the hand or be otherwise released so as to have a tendency to "fly up" or wind up at an excessive speed, the increased speed of rotation of the roller will result in the added centrifugal force throwing the dog 6 outwardly so that its abutment 16 will pass over and engage the lug 5, as seen in Fig. 1, thereby stopping or locking the roller against further rotation. This will avoid injury to the shade, as well as eliminating the annoyance of unwinding same when completely wound up. By the provision of a single lug 5, the remainder of the circular path of the dog 6 is unobstructed, so that the dog is given a large arc in which to move outwardly to a position to engage the lug 5. The portion 17 in contacting with the pin or spindle 3 will limit the inward movement of the dog under the tension of the spring, when the roller is turned to release the dog from the lug 5.

In Fig. 5 the stop 5' is shown as being struck from the bracket 4' near the base 45 thereof so as to lie behind the roller and afford greater strength and to also require less material or stock for the bracket.

Having thus described the invention, what is claimed as new is:—

1. A shade roller stop comprising a cap to be fitted on the end of a roller for rotation therewith, a disk separate from and fitted within the cap to rotate with it, and a dog carried by the disk between it and the cap and swingable outwardly through the cap to engage a fixed stop.

2. A shade roller stop comprising a cap to fit on and rotate with the end of a roller, a disk separate from and fitted within the cap to rotate with it, and a dog carried by the disk movable outwardly through the cap for engaging a stop to stop the roller.

3. A shade roller stop comprising a cap to fit on and rotate with the end of a roller, a disk separate from and fitted within the cap to rotate with it, a dog carried by the disk movable outwardly from the cap for engaging a stop to stop the roller, and a spring for the dog also carried by said disk for returning said dog.

4. A shade roller stop comprising a cap, adapted to fit over the end of a roller, a disk within said cap having a marginal flange with portions engaging through the cap for securing the disk and cap together, a dog pivotally carried by said disk between it and the cap, the rim of the cap having a slot through which said dog is movable outwardly for stopping the roller, and a spring carried by the disk and disposed between said dog and flange for retracting the dog within the cap.

In testimony whereof I hereunto affix my signature.

WALTER C. MOORS.
